REGISTER FOR COLD AND HOT AIR DUCTS

Filed Feb. 15, 1928

INVENTOR
John R. Thomas
BY his ATTORNEY

UNITED STATES PATENT OFFICE

JOHN A. THOMAS, OF ROCHESTER, NEW YORK

REGISTER FOR COLD AND HOT AIR DUCTS

Application filed February 15, 1928. Serial No. 254,380.

The present invention relates to registers for cold and hot air ducts and an object of the invention is to provide a novel means of connecting the front plate of a register to the frame which connects with the duct so that the front plate may be shifted in order to occupy a slightly different position from the frame when the latter connects with a duct which is out of alignment.

10 To this and other ends, the invention consists of certain parts and combinations of parts, all of which will be hereinafter described: the novel features being pointed out in the appended claims.

15 In the drawings:

Fig. 1 is a front view showing the front plate in dotted lines shifted slightly with reference to the frame in order to line up vertically when the frame is secured to the stack in a position slightly off the vertical;

Fig. 2 is a rear view showing the valve in position and the frame vertically aligned with the front plate;

Fig. 3 is an enlarged view of one of the sides of the frame showing the adjustable anchoring device for the front plate;

Fig. 4 is a sectional view showing the manner in which the front plate connects with a frame attached to a stack head on the line 4—4, Fig. 6;

Fig. 5 is a detail view showing the manner in which the register frame is secured to a stack head on the line 5—5, Fig. 7;

Fig. 6 is a view of the register embodying the present invention in place on the wall; and

Fig. 7 is a view of the open end of the flue head with the rectangular frame positioned therein.

40 In the illustrated embodiment, 1 indicates the front plate of a register provided with a central grille or open work. Associated with this front plate is a frame 2 which is rectangular and has its sides formed from sheet metal, the flat faces of which are paral-

lel with the opening of the frame. This frame may be secured into the usual stack head 3 by a number of strips of ductile metal 4 which are secured at 5 to the inner face of the stack head, then around the rear edge of the frame at 7 and then outwardly over the inner face of the frame at 8, the outer end being extended at 9 over the forward edge of the frame at 2, as illustrated in Fig. 5. On the rear face of the front plate 1 may be pivotally mounted at 10 a valve or shutter 11 controlled in any suitable manner. The type of register just described is a commercial structure at present in extensive use. The disadvantage of this type of structure now in use is, that the frame 2 is, in many instances, thrown out of alignment, due to the fact that the stack head 3 in which the frame 2 fits is positioned out of alignment. With the means heretofore employed for securing the front plate to this rectangular register frame, this misalignment of the register frame is imparted to the front plate so that the latter also becomes out of alignment.

50 In the present invention, a novel means is provided for connecting the front plate 1 with the rectangular frame 2 in such a manner as to permit the front plate to be properly positioned or aligned, notwithstanding the fact that the rectangular frame 2 is out of alignment. This means comprises two aligning devices mounted on two opposite walls of the frame 2 so as to be adjustable longitudinally of said walls in order to be engaged by fastening devices 12 passed through the front plate 1 into the anchoring devices. In this embodiment of the invention each of the anchoring devices embodies an outwardly extending anchoring lip 13 formed with an opening 14 through which the fastening devices 12 pass as shown in Fig. 4. Each anchoring device also embodies portions movable on the frame 2 and to this end the frame 2 is provided with a longitudinally extending opening 15 in one of its sides through

which a portion 16 of an anchoring device extends, the anchoring device having a portion 17 cooperating with the outer face of the frame between the lip 13 and the outer portion 16 and also having a portion 18 extending from the portion 16 outwardly and cooperating with the inner face of the side piece of the frame 2. This construction permits the anchoring device to be shifted longitudinally in the slot 15 so that by the combined adjustment of the two anchoring devices the angle of the front plate with reference to the frame 2 may be changed, thus permitting the front plate to be lined up in such a manner that it will conform to the condition in which it may be situated. The screw 12 is tapered, and it is easier to line up a tapered screw with the opening 14 and start the screw, than it is to perform the same operation with a blunted bolt. If the wall is of wood it forms an additional anchoring means, but in most cases the walls are of plaster, and in that event the support of the register depends entirely upon the screw engaging the element 13. The adjustment of the register is made, and not until after such adjustment has been made is the screw turned down so that it passes into the wall.

What I claim as my invention and desire to secure by Letters Patent is:

1. A register for use in connection with a flue head comprising a rectangular open frame arranged to fit within the flue head, a front plate, fastener anchoring devices adjustable longitudinally of and on two opposite sides of the frame and projecting beyond the outer faces of the flue, and fasteners for securing the front plate to the anchoring devices.
2. A register for use in connection with a flue head comprising a rectangular open frame arranged to fit within the flue head formed of sheet material, the flat faces of which are arranged parallel with the opening through the frame, fastener anchoring devices adjustable on two opposite sides of the frame longitudinally of such sides and projecting beyond the outer faces of the flue head, a front plate, and fasteners for securing the front plate to the anchoring devices.
3. A register for use in connection with a flue head comprising a rectangular open frame arranged to fit within the flue head having longitudinally extending slots in opposite sides thereof, fastener anchoring devices having portions operating in said slots to permit the anchoring devices to be adjusted longitudinally of said side pieces of the frame, a front plate, and fasteners for securing the front plate to the anchoring devices.
4. A register for use in connection with a flue head comprising a rectangular open frame arranged to fit within the flue head having one side provided with a slot extend-

ing longitudinally of the side, a fastener anchoring device adjustable in said slot, a front plate and a fastener for securing said front plate to the fastener anchoring device.

5. The combination with a flue head, an open rectangular frame fitting in the flue head and means for securing the frame in the flue head, of a front plate, and screw anchoring means adjustably secured to and supported by said frame to permit the shifting of the front plate in its plane in order that the front plate may occupy a different angular position from the frame and screws for securing said front plate to the screw anchoring means.
